ARTHUR J. BAKER, OF TOLEDO, OHIO, ASSIGNOR TO THE WILLYS-OVERLAND COMPANY,
OF TOLEDO, OHIO, A CORPORATION OF OHIO

TIMING GEAR

Application filed December 17, 1923. Serial No. 681,168

This invention relates to improvements in timing gears for automotive gas engines, having particular reference to constructions in which the generator is supported by what is known as the S. A. E. mounting, that is, a mounting in which the generator is attached at its front end only to the engine casting, producing what is known as a long "over-hang" behind, thus leaving the rear end free to vibrate and to move under the influence of the rotary motion of its armature and of the timer and distributor mounted upon its rear end. This latter condition produces what is known in the art as "thrashing" of the generator gear, that is, regularly recurring motions of the gear other than its intended rotation upon its own axis. There is also a certain "thrash" and jerkiness in the crank-shaft gear, which is transmitted to the cam-shaft gear and added to some inherent thrash in the latter gear. Probably the thrash of the cam-shaft and generator gears in mesh with each other, combined in timed relation, produces a different and possibly greater noise than would be produced otherwise. At any rate, the noise is objectionable, and it is the object of this invention to reduce it.

A specific object of the invention is to construct a gear for use as one element in a gear train, in such a manner as to render the operation of the train relatively noiseless.

Another object of the invention is to provide a noiseless gear of simple construction, the parts of which may be quickly and accurately assembled and applied to a power shaft, the nature of the construction being such as to reduce the cost of manufacture to a minimum in a gear of this type.

Other objects relating to details of construction and economies of manufacture, will appear from the description to follow, covering that embodiment of the invention, which, for the purpose of the present application, I have illustrated in the accompanying drawings, in which:

Figure I is a side elevation of an internal combustion engine, including a generator, to the driven shaft of which the improved gear is shown applied.

Fig. II is a view in elevation of a non-metallic ring employed in the construction of the gear, to render it practically noiseless.

Fig. III is a sectional elevation through the gear, taken on the line III—III of Fig. IV.

Fig. IV is an end elevation of the gear shown in Fig. III.

Fig. V is a sectional elevation of the gear disc shown keyed to the generator shaft in Fig. III.

Fig. VI is an end elevation of the disc shown in Fig. V.

Fig. VII is a sectional plan taken on line VII—VII of Fig. IV, and

Fig. VIII is a plan view of the generator shown in Fig. I, illustrating the manner of mounting the same upon the engine casing.

In accordance with my invention, the generator gear is formed of a plurality of inter-engaging parts, one part being adapted for connection to a power shaft, and another having the desired number of teeth formed thereon, while a third is constructed of non-metallic material and adapted to transmit motion from either of said first-mentioned parts to the other, all of the parts being mounted upon a single power shaft, and all retained in proper relation preferably by common means for holding them together and for preventing longitudinal displacement of the same upon the shaft.

In the drawings I have shown an internal combustion engine having the usual cam and crank-shafts (not shown) mounted within the engine casing or frame 10, to which is secured the generator 11, the shaft 12 of which is provided with a gear 13 constructed in accordance with my invention and adapted to be driven from the crank shaft 14 through suitable intermediate gears (not shown), said gears being enclosed in the casing 15, preferably comprising a part of the engine frame or casing. The gear 13 comprises three main portions including the disc 16, flanged member 17 having the desired number of teeth thereon, and the intermediate non-metallic ring 18 formed preferably of hard fiber, but which may be made of any suitable non-metallic material, whether of one or more sections. This ring 18 should be "rela-

tively hard", which term is intended herein to cover any non-metallic material which is unyielding to an extent sufficient to prevent relative angular motion between the metal disc 16 and flanged ring 17 of the gear. The flanged member 17 is recessed to receive the peripheral edge portion of the disc 16, as shown in Figs. III and VII. The disc is provided with a sleeve or hub 19 inserted upon the portion 20 of the generator shaft and is secured by a key 21 rigid upon the shaft and projecting into the slot 22 formed in said sleeve. The non-metallic or fiber ring 18 is provided preferably with four holes or recesses 23, two of which are adapted to receive pins or projections 24 extending inwardly from the disc 16, and the other two adapted to receive similar pins or projections 25 extending in an opposite direction from the flanged member 17. Through the medium of these pins, the flanged member 17 is adapted to drive the fiber ring 18, and the latter to drive the disc 16, which in turn drives the generator shaft 12. Thus power is transmitted to the generator shaft or to any other shaft to which the gear may be applied, by means of a non-metallic driving ring located within the enclosure or chamber formed by the fitting together of the disc 16 and flanged member 17, the latter of which is provided with a bore large enough to receive the free end of the sleeve 19 on the disc 18. The pins or projections 24 and 25 are preferably riveted in position upon the disc and flanged member as indicated at 26 in Figs. III and VII.

The gear receiving portion 20 of the generator shaft is provided with a shoulder 27 adapted to prevent inward movement of the gear, while outward movement of the gear is prevented by a washer 28 on the reduced portion 29 of the shaft, the washer being secured by a nut 30, and sufficient play being allowed between the shoulder and washer to prevent clamping of the flanged member 17 upon the disc 16. The washer serves to both hold the several parts of the gear in assembled position, and to prevent outward displacement of the same upon the shaft, it being only necessary to loosely assemble the several portions of the gear before applying the latter to the shaft.

The driving ring 18 may be constructed of slightly yieldable material, but preferably comprises a fiber ring having the desired degree of hardness and rigidity.

The generator 11, as before stated, is supported by what is known as the S. A. E. mounting, being secured at its front end to the portion 15 of the engine casing containing the timing gears, as by means of the bolts 31 shown in Figs. I and VIII. The generator is therefore supported at its front end only and is held in spaced relation to the engine frame or casing at all other points,

thus producing the "over-hang" mentioned above. One of the important features of the present invention is the combination of this particular type of generator mounting and an anti-thrash gear of the kind shown and described herein. 70

While I have shown in considerable detail, a specific embodiment of my invention, it is to be understood that this showing and description are illustrative only, and that I do not regard the invention as limited to the details of construction illustrated or described, except insofar as I have included such limitations within the terms of the following claims, in which it is my intention to claim all novelty inherent in my invention broadly, as well as specifically. 75 80

I claim as my invention:

1. In combination, a power shaft, a gear upon the shaft including a relatively rigid non-metallic ring and two oppositely positioned members, each of which is independently connected with the ring and one of which is provided with teeth, and a clamping member serving to hold the parts of the gear together and adapted to prevent longitudinal displacement of said parts upon the shaft. 85 90 95

2. In combination, a power shaft, a gear upon one end of the shaft including a fiber ring and driving and driven members independently connected therewith at points substantially equidistant from the center of the ring, and means upon said shaft end for clamping the gear thereon. 100

3. In combination, a power shaft, a gear upon one end of the shaft including three separate members, two of which are provided with independently mounted pins projecting in opposite directions, the free ends of the pins being disposed within recesses formed in the third member, and common means upon said shaft end for holding said members together and for holding them against displacement upon the shaft. 105 110

4. In combination, a power shaft, a gear upon one end of the shaft comprising a non-metallic ring, separate members mounted upon each side of the ring and forming an enclosure therefor, each of said members having pins projecting therefrom into recesses formed in the ring, the pins of each of said members terminating short of the opposite member, and common means for holding said parts together and for securing them upon said shaft. 115 120

5. In combination, a power shaft, a gear upon one end of the shaft including a disc keyed thereto, a flanged member adapted to receive the disc and having teeth formed thereon, a non-metallic ring interposed between the disc and flanged member, pins extending in opposite directions from said disc and said flanged member and adapted to engage said ring in recesses formed therein, a 125 130

washer upon the free end of the shaft, and means for clamping said washer upon said gear.

6. In combination, a power shaft, a gear comprising a plurality of inter-engaging portions assembled upon one end of the shaft and including a shock absorbing ring, and common means for holding said portions together and for retaining them against longitudinal displacement upon the end of the shaft.

7. In combination, a gear comprising a disc having a sleeve adapted to be keyed upon a shaft, a flanged member having teeth formed thereon and provided with a bore adapted to receive the free end of said sleeve and also having a recessed portion adapted to receive the peripheral portion of the disc, a ring constructed of relatively hard, non-metallic material positioned between said disc and flanged member and adapted to surround said sleeve, means operatively connecting said flanged member with said ring, means operatively connecting the ring with said disc, and clamping means for maintaining the assembled relation of the gear parts, said clamping means having a stop for preventing cramping of said parts.

8. In combination, a gear comprising a disc having a sleeve adapted to be keyed upon a shaft, a flanged member having teeth formed thereon and provided with a recess adapted to receive the peripheral portion of said disc, a ring constructed of relatively hard, non-metallic material inserted upon said sleeve between the disc and flanged member, driving connections between the flanged member and the ring and between the ring and said disc, means for holding the gear parts in assembled relation, and means for preventing the cramping of the ring between the disc and flanged member.

9. In combination, a gear comprising two metal sections positioned one upon another and adapted to form a closed chamber between them, a relatively hard non-metallic ring disposed within said chamber, driving connections between one of said sections and the ring, independent driving connections between the ring and the other of said metal sections, and means in engagement with the metal sections for restraining relative axial movement.

In testimony whereof I affix my signature.
55 ARTHUR J. BAKER.
